[57] **CLAIM**

The ornamental design for a marching band teaching-sound system case, as shown and described.

DESCRIPTION

FIG. 1 is a front perspective view of a marching band teaching-sound system case showing my new design;
FIG. 2 is a front elevational view thereof;
FIG. 3 is a top plan view thereof;
FIG. 4 is a left side elevational view thereof;
FIG. 5 is a right side elevational view thereof;
FIG. 6 is a rear elevational view thereof;
FIG. 7 is a rear perspective view of the case with the rear cover open;
FIG. 8 is a rear elevational view thereof; and
FIG. 9 is a left side elevational view thereof.
